United States Patent Office

Des. 219,500
Patented Dec. 15, 1970

219,500

TIRE

Eric C. Bartlett, Erdington, Birmingham, England, assignor to The Dunlop Company Limited, Birmingham, England, a corporation of Great Britain

Filed Aug. 11, 1969, Ser. No. 18,625

Claims priority, application Great Britain Feb. 26, 1969

Term of patent 14 years

Int. Cl. D12—14

U.S. Cl. D90—20

FIG. 1

FIG. 2

FIG. 3

FIG. 1 is a perspective view of the tire of my new design,

FIG. 2 is a fragmentary perspective view,

FIG. 3 is a fragmentary plan view.

It is to be understood that the tread pattern continues as shown throughout the circumference of the tire and the sidewall opposite to that shown in FIG. 1 is the same.

I claim:

The ornamental design for a tire, as shown and described.
